UNITED STATES PATENT OFFICE.

JOHANN WICKELAND, OF BLUMENTHAL, GERMANY.

RAILWAY SIGNAL.

Application filed December 15, 1926, Serial No. 154,878, and in Germany February 16, 1925.

This invention relates to a railway signaling device and consists in the provision of a stationary search-light and of reflectors arranged in the engine so as to catch the light-rays and illuminate the driver's cab with the same.

The search-light is preferably suspended over the track and provided with means for throwing light perpendicularly on to the track as well as obliquely thereto. By this arrangement a repetition of signals will be obtained which cannot fail to attract the driver's attention.

Fig. 1 of the accompanying drawings represents a side view of the search-light arrangement,

Fig. 2, a view at right angles to Fig. 1,

Fig. 3, a view showing the effect on the engine of the vertical light-rays,

Fig. 4, a view showing the effect of oblique light-rays on an advancing engine, and

Fig. 5, a view showing the effect of oblique rays on an engine which has passed the search-light.

Erected at the side of the railway track *b* is a mast *c* having an arm *d* which overhangs the track so that it can be used as a means for suspending a search-light *a* over the track at a sufficient height above the latter for being clear of the traffic. The railway engine *g* is provided with a suitable arrangement of reflectors adapted to catch the rays of the search-light and illuminate the driver's cab therewith as a warning to the driver.

The searchlight *a* consists of a double projector containing a source of light *f*, said projector comprising light beam projectors *e* and *e'* arranged at an angle to each other.

The projector *e* is disposed to project a light beam perpendicularly straight down onto the railway track while the projector *e'* is disposed to project an oblique beam downwardly onto the track in the direction of the track.

By reason of the oblique reflector and double projector arrangement described it will be seen, also, that each time a light beam strikes the reflector an incident light flash will be reflected into the cab, one of the flashes being short and followed by the other and longer one, or vice versa, according to the direction of travel of the locomotive along the track or the arrangement of the

projector elements as desired with respect to up and down travel directions. These signal flashes may have certain significancies. Thus, for example, at certain crossings or danger points the long flash may be given first to indicate the character of the crossing so as to give the engineer ample time to get his train under control before the short flash is given, which may be a warning at a certain distance from the station that at this point the train speed, if not reduced below normal running speed, should be reduced to a certain speed; or the short flash may first be given as a caution or warning signal followed by the long flash which may be of such duration as to obviate the possibility of the engineer ignoring it if he has ignored the short signal. Of course, the signals may be given other significancies and by disposing the projector *e'* to project the oblique beam so as to strike the reflecting mirror at any given distance from the mast the length of the beam and time duration of the long flash may be varied as desired.

Fig. 3 shows an engine reflector *h* arranged so as to catch the perpendicular light-rays for illuminating the cab. Fig. 4 shows a reflector *i* for dealing with oblique rays thrown against an advancing train, and Fig. 5, a reflector *k* which catches oblique rays received from behind the engine. Thus a repetition of signals may be given to ensure the driver's attention, and both signals may be given from the front of the locomotive, or one from the front and the other from the rear, according to the desired arrangement of the projectors *e* and *e'* with relation to each other and to the trackway.

The search-light is controlled from the signal box, and means may be provided for changing the colour of the light so as to indicate "stop" or "clear". For instance a bright white light, strong enough to penetrate a fog, may be used as a stop signal, and a coloured light may be used to indicate that the line is clear.

I claim:

In a railway signaling device, a locomotive carrying a light reflector arranged at an oblique angle between the vertical and horizontal for reflecting light beams from a relatively elevated external source into the cab thereof, and signal projecting means comprising

a mast alongside the track, an arm extending from the mast and overhanging the track, and a double projector on said arm and above the track and comprising a pair of projectors arranged for casting light beams at an angle to each other, one vertically down upon the track and the other

obliquely downward in a direction longitudinally of the track so as to be intercepted by said light reflector to respectively reflect 10 relatively short and long flashes from said beams into the cab in the travel of the locomotive along the track.

JOHANN WICKELAND.
